US0D1110807S

(12) **United States Design Patent** (10) Patent No.: **US D1,110,807 S**
(45) Date of Patent: ** Feb. 3, 2026

(54) **PORTABLE INSULATING CONTAINER**

(71) Applicant: **YETI Coolers, LLC**, Austin, TX (US)

(72) Inventors: **Kyle Ellison**, Austin, TX (US); **Rafael Moreno**, The Woodlands, TX (US); **Colin Darling**, Austin, TX (US); **Evan Goldberg**, Austin, TX (US); **Lane Van Wagner**, Dripping Springs, TX (US)

(73) Assignee: **YETI Coolers, LLC**, Austin, TX (US)

(**) Term: **15 Years**

(21) Appl. No.: **29/898,567**

(22) Filed: **Jul. 28, 2023**

Related U.S. Application Data

(63) Continuation of application No. 29/849,643, filed on Aug. 12, 2022, now Pat. No. Des. 1,039,915, which is a continuation of application No. 29/800,138, filed on Jul. 19, 2021, now Pat. No. Des. 964,110, which is a continuation of application No. 29/759,885, filed on Nov. 25, 2020, now Pat. No. Des. 927,939, which is a continuation of application No. 29/650,922, filed on Jun. 11, 2018, now Pat. No. Des. 904,128, which is a continuation of application No. 29/647,444, filed on May 13, 2018, now Pat. No. Des. 869,244.

(57) **CLAIM**

The ornamental design for a portable insulating container as shown and described.

DESCRIPTION

FIG. 1 is a front view of a portable insulating container showing our new design;

FIG. 2 is a rear view thereof;

FIG. 3 is a right side view thereof;

FIG. 4 is a left side view thereof; and,

FIG. 5 is a bottom view thereof.

The broken lines in the figures illustrate portions of the portable insulating container that form no part of the claimed design.

1 Claim, 5 Drawing Sheets
